J. LE R. BANKS

METHOD FOR MAKING RECORDS

Original Filed July 22, 1924

INVENTOR.
Joseph L. Roy Banks
BY
Albert Rosenberg
ATTORNEY.

UNITED STATES PATENT OFFICE.

JOSEPH LE ROY BANKS, OF BALTIMORE, MARYLAND, ASSIGNOR TO THE BOLMONICA
MUSIC CO., OF BALTIMORE, MARYLAND.

METHOD FOR MAKING RECORDS.

Application filed July 22, 1924, Serial No. 727,466. Renewed November 15, 1927.

My invention relates to methods for making perforated sheets or for marking them to be perforated or printed such as are used for notes controlling means or master sheets 5 for notes controlling means for player musical instruments, type setting machines, type casting machines, etc., through the perforations of which air is either drawn or forced to either operate or control the operation 10 of the tones of musical instruments; or the operation or the control of the operation of type setting, or type casting machines, etc., or the control or the operation of perforating or other punching, marking 15 or printing machines, etc.

The objects are:

First. To provide a new method of manufacture. 20 2nd. To provide a new method for manufacturing perforated sheets or for marking sheet materials. 25 3rd. To provide a new method for manufacturing perforated sheets by electric means, or for marking them, or for printing them.

4th. To provide a method for manufacturing perforated sheet materials or for marking or printing sheet materials by a combination of pneumatic and electrical 30 devices.

5th. To provide a method for perforating or marking note controlling sheets for player musical instruments, by playing the instruments and transmitting the tones 35 through pneumatic tubes to marking, perforating, or printing devices, to perforate, print or mark the sheets.

6th. To provide a method for perforating or marking note controlling sheets for 40 player musical instruments, etc., by playing the instrument and utilizing the same air or wind which operates the tones to operate pneumatic and electric means for either perforating the sheets or for marking or printing them.

7th. To provide an electric means for a new method for perforating or marking sheet materials.

8th. To provide a pneumatic means for a new method for perforating, marking or printing sheet materials.

To these ends, I provide musical instruments or wind instruments as they may be

termed, with pneumatic tubes leading from the tones producing devices or from the passageways leading to the tones producing devices, to devices operable by pneumatic means, carrying means for perforating, marking or printing sheet materials while the sheet material is moved under and past the perforating, marking or printing devices, at the proper rate of speed. 55

Also provides means operable by pneumatic means controlled by pneumatic tubes leading from tones producing devices, whereby perforating, printing or marking devices are operated. 60

Instead of musical instruments, I may use a device without tones producing means and mark the passageways connected with 70 pneumatic tubes with numerals or letters of the alphabet or characters of a musical scale.

In the description of the machine I use to accomplish my method, it is obvious that a pencil or other marker may be used in 75 place of the punch and likewise a stencil printing device can be substituted without changing the machine except to close up the die holes.

Referring to the drawings,— 80 Fig. 1, is a sectional side elevation of my machine showing the method I use in making perforated sheets, or for marking or printing them.

Fig. 2, is a side elevation of my electrical 85 tappet lever or key showing the reversal of the contact points for closing the circuit when the air pressure is decreased in the air chamber.

Fig. 3, is a view of the bottom of my machine bed and drums for winding the sheet material to be perforated, marked, or printed. 90

Referring to the numerals,— 95 1 is the leg of the bed 90 through which the wires 6 and 7 attached to the electrodes 2 and 3 respectively pass in their respective holes 4 and 5 to the helix 46 forming the electromagnet with the core 45, and to the binding nuts 16 and 17 on the insulating 100 post 8, the nut 16 being in electrical contact with the bracket 14 carrying the contact point 18. The insulating post 8 is fastened in the bed 90 by the nuts 10 and 9 threaded onto the insulating post 8. Secured to the insulating post 8 is fastened the 105

bracket 11 by the nuts 12 and 13 threaded onto the insulating post so as to permit of the bracket's adjustment, and in this bracket 11 is fitted the rest support 19 by threading into the bracket 11 and secured in position by the nut 20 threaded onto the rest support 19.

Between the brackets 11 and 14 with the contact point 21 adjusted below the contact point 18, and fixed to the electric lever key 22 resting upon the rest support 19 at one end and upon the diaphragm of rubber 25 or other flexible insulating material, and at its other end 23 is pivoted or hinged in the standard 24' by the pin 23'; and this standard 24' is fixed to the bed 90 by the bolt 34 passing through the insulating bushing 24'', the insulating washer 33 and the insulating nut 35 threaded onto the bolt 34; under the head 24 of bolt 34 is secured the other end 70 of the helix 46 completing the circuit from the battery 3' when the contact points 18 and 21 are closed.

The diaphragm 25 is secured by a ring or tube 25' on its inside pressing it against the receptacle 28 which is flanged at 27 for securing it to the bed 90 by the bolts 26 and 32.

25'' is the chamber of the diaphragm 25 which leads out of the nipple 29 through the outlet 31 to the tubing 30 secured at one end to the said nipple 29, and this tubing 30 which is flexible and preferably of rubber is secured at its other end 30' to the nipple 30'' secured in the musical instrument 91 and to the reed block 96 and the air passageway 92 under the reed plate 94 carrying the reeds 95. 93 and 97 are the wind chests for the musical instrument 91. 98 and 99 etc., are other nipples leading to other passageways of the musical instrument 91 whereby other flexible tubes may be connected to operate other diaphragms and electrical levers with contact points and connections for operating other electromagnets and punches or marking devices.

It is contemplated to use a series of punches to correspond with the number of tones of the musical instrument; or to correspond with the scale of musical tones; or to the numerals; or to letters of the alphabet.

The electromagnet 45—46 is secured to the bed 90 by the bolt 47. 42 is the standard secured by the bolt 36 to the bed 90 and in which standard 42 is pivoted the tappet lever armature 44 by the pin 48.

This lever armature 44 is normally held in position for operating by the spring 44' secured to the standard 42 by the bolt 70', and the punch 71 secured to its slide or guide 52 slidably mounted in its standard 53 is normally held in position for operating by its spring 55 secured to the standard 53 by the bolt 56 enabling the spring 55 to hold up the pin 54 secured in the guide 52.

Below the bed 90 the feed rollers 68 and

68' and 72 and 72' are suitably secured to the bed 90 and between which the paper or other material 41 to be punched passes from the reel 65 to the other reel 68''. The reel 65 is supported in the hanger 63 secured to the leg 61 of the bed 90 by the bolts 60 and 62, by the spindle 64 secured to the crank 66. The reel 68'' is secured to the spindle 67 inserted in suitable bearings in the hanger 38 fastened to the bed 90 by the bolt 40 threaded into the nut 39, and the spindle 67 is secured to the crank 69. The die plate 51 is secured to the bed 90 by the bolt or rivet 49 and is so arranged that the paper 41 passes between the die plate 51 and the bed 90 and between the feed rollers 68—72' and 68—72. 36 is the head of the bolt 40. 38 is a bracket attached to the hanger 68''.

In operating the perforating machine by my process, the wind instrument 91 is played upon by suitable means and the air operating the tones will in part expand the diaphragm 25 by increasing the pressure in the tube 30 and in the chamber 25' and thereby raise the lever key 22 which closes the contacts 21 and 18 making the circuit to the electromagnet 46—45, and magnetically drawing down the armature lever 44 drives the guide 52 carrying the punch 71 through the paper 41, and releasing the punch 71 when the pressure is diminished in the chamber 25'' under the diaphragm 25.

In Figure 2 the lever 22 is arranged with the contact 21 on the reverse side; and the contact bracket 14 with its contact point 18 is reversed and arranged under the lever contact point 21, so that when air is drawn from under the diaphragm 25 as when by suction playing of the instrument 91, thereby relieving the pressure under the diaphragm 25 causing the lever 22 to fall and close the contacts 18 and 21 to make the circuit to the electromagnet 46—45, thereby operating the punch 71 through the paper 41 in the same way as before.

I do not care to limit myself to any particular design or construction except as defined by my claims.

I may use any materials to accomplish the purpose of my claims. Instead of punching the material sheets, I may simply mark them, or I may print them by having a carbon sheet placed on top of the moving sheet and closing the die holes and substituting other devices for the punch attached to the guide 52.

I claim:

1. A method for making records, consisting of causing air currents to move and vary the air pressure in chambers and thereby operating diaphragms to manipulate electrical circuits to operate recording devices and moving a sheet to receive the record.

2. A method for making records, consisting of causing air currents to move in

- opposite directions to vary the air pressure in chambers and thereby operating diaphragms to manipulate electrical circuits to operate recording devices and moving a sheet 5 to receive the record.
3. A method for making records, comprising pneumatically varying the air pressure in chambers and thereby operating diaphragms to manipulate electrical circuits to 10 operate recording devices and moving a sheet to receive the record.
4. A method for making records, comprising causing air currents to move through a musical instrument to produce sounds and 15 by the air currents jointly varying the pressure in chambers thereby operating diaphragms to manipulate electrical circuits to operate recording devices and moving a sheet to receive the record.
- 20 5. A method for making records, comprising causing air currents to move in opposite directions through a musical instrument and jointly, by the air currents varying the air pressure in chambers and thereby operating
- diaphragms to manipulate electrical circuits 25 to operate recording devices, and moving a sheet to receive the record.
6. A method for making records, comprising causing air currents to move through a musical instrument to produce sounds, and 30 jointly, by the air currents vary the air pressure in chambers and thereby operate diaphragms to manipulate electrical contacts to manipulate electrical circuits to operate recording devices, moving a sheet to 35 receive the record, and rolling up the record.
7. A method of recording a musical note upon a sheet music roll which comprises passing a current of air through a passageway in a musical instrument, corresponding 40 to the note to be recorded, causing by movement of said air movement of a pressure responsive diaphragm, utilizing the movement of said diaphragm to complete an electrical circuit, said circuit actuating a recording 45 device, and recording the note upon a music roll sheet.

JOSEPH LE ROY BANKS.
